UNITED STATES PATENT OFFICE.

SAMUEL E. BARNEY, OF NEW HAVEN, CONNECTICUT.

DESIGN FOR RUFFLING.

Specification forming part of Design No. 7,077, dated December 30, 1873; application filed December 2, 1873.
[Term of Patent 7 years.]

To all whom it may concern:

Be it known that I, SAMUEL E. BARNEY, of New Haven, in the county of New Haven and State of Connecticut, have invented a new Design for Ruffling; and I do hereby declare the following, when taken in connection with the accompanying drawing and the letters of reference marked thereon, to be a full, clear, and exact description of the same, and which said drawing constitutes part of this specification, and represents a short piece of the ruffle.

This invention relates to a design for ruffling made from any suitable fabric, particularly to that class formed by a succession of plaits; and it consists in the peculiar relative form and position of the plaits, as shown in the accompanying illustration, and which I will proceed to describe.

A are broad plaits, alternating with which are narrow plaits B, and between the broad and narrow plaits a portion or space, a, is left single or not plaited. The edge may be ornamented in any desirable manner, but such ornamentation is no part of this design, the alternating broad and narrow plaits, with a space between, being the characteristic features of this design.

I claim as my invention—

The design for plaited ruffle, substantially as herein described, and shown in the accompanying illustration.

SAML. E. BARNEY.
